SAFETY MEANS FOR A GASEOUS FUEL BURNING STOVE

Karl Gunnar Ross, Enskede, Sweden, assignor to Aktiebolaget Bahco, Stockholm, Sweden, a corporation of Sweden

Application December 7, 1955, Serial No. 551,577

Claims priority, application Sweden February 21, 1955

3 Claims. (Cl. 126—44)

The present invention relates to gaseous fuel burning stoves, and more particularly to gaseous fuel burning stoves having a fuel container and a burner screwed in the top of the container.

The operation of such stoves requires that the fuel container is comparatively frequently replaced or at least refilled. This involves removal of the burner and the parts joined thereto such as a control valve and a support for a cooking vessel. Accordingly, it is highly desirable that the burner is readily and conveniently removable. However, accidental loosening of the burner due to jars or careless handling must be prevented or at least impeded as it would cause escape of gas from the container. Escape of gas cannot be entirely prevented by the provision of an automatically closing valve in the mounting socket of the container for the burner as the movable component of such valve has to move a certain distance before it closes the valve. Due to the conditions under which stoves of the kind here involved are generally operated, lock nuts or washers and similar retaining or safety means involving the use of tools and/or requiring a certain technical skill are not suitable.

One of the objects of the present invention is to provide a novel and improved safety means for stoves of the general kind above referred to, which on one hand does not interfere with a convenient removal of the burner without the use of tools and on the other hand, impedes the accidental loosening of the burner.

Another object of the invention is to provide a novel and improved safety means which becomes automatically effective when the burner is screwed into position and is automatically released when the burner is intentionally unscrewed, but resists an accidental loosening of the burner.

Still another object of the invention is to provide a novel and improved safety means which engages the container with a frictional grip when the burner is screwed into position thereby effecting an impositive lock between the burner and the container.

Other and further objects, features and advantages of the invention will be pointed out hereinafter and set forth in the appended claims forming part of the application.

In the accompanying drawing a preferred embodiment of the invention is shown by way of illustration and not by way of limitation.

In the drawing:

Fig. 1 is an isometric view of a gaseous fuel burning stove equipped with safety means according to the invention.

Fig. 2 is an elevational view of the upper part of the stove on an enlarged scale showing the burner and the parts joined thereto in position ready for screwing the burner into position, and

Fig. 3 is an elevational view similar to Fig. 2, but showing the burner and the parts joined thereto in the screwed-in or operational position.

Referring now to the figures in detail, the stove as illustrated comprises a container 1 for a liquid petroleum gas,

2

such as liquid propane, for example; a burner 3 having a threaded portion 3' for screwing the burner into the top of the container 1; control valve 2 with a valve member 2'; a cooking vessel support 4; and mounting means including the safety means of the invention mounting support 4 and secured to the casting of valve 2 or any other suitable part joined to the burner. 8 is the automatically closing valve in the mounting socket 9 of the container 1. This socket is provided with a valve seat 10 and an opening 11 in the side wall. 12 is a pin, connected to the closing valve and by means of this pin 12 the valve 8 is opened against the action of a spring 13 when the threaded portion 3' of the burner is screwed into the mounting socket 9. 14 is a safety valve mounted on the container 1. 15 are air ports for combustion supporting air.

By way of example and without limitation, apparatus like that illustrated in Figs. 1, 2 and 3 and described above has been constructed in which the diameter of the casing 1 is about five and one-half inches and the overall height is about seven and three-eighths inches, the threaded opening at the top thereof being about nine-sixteenths of an inch. The overall diameter of the burner unit is about five and one-half inches. When the burner unit is secured in position on the casing, the overall height of the entire ensemble is about ten and one-half inches.

The mounting and safety means are shown as comprising three rigid legs 5 depending from support 4. However the legs may be secured to another suitable part associated with the burner. It is only essential that the legs are fixedly joined to the burner. As can best be seen in Fig. 3, the length of each leg is such that it does not reach the top of the container when the burner is fully screwed in position. An elastic sleeve 6 made for instance of rubber or a rubber composition is slipped upon the free end of each leg 5 axially protruding therefrom. The length of sleeves 6 is such that the protruding end thereof engages the top of the container in the screwed-in position of the burner with frictional pressure as is indicated at 7 in Fig. 3 by the axial deformation of the sleeves.

As is apparent from the previous description, the legs or more specifically the part thereof engageable with the container are axially yieldable. It is evident that the same effect can be obtained for instance by providing at the respective ends of the legs spring loaded plungers, the engaging ends of which may be covered with a high friction material such as rubber to increase the frictional engagement between the legs and the container.

The compressed ends of sleeve 6 will resist unscrewing of the burner due to jars or careless handling, but will not prevent turning of the burner by an intentionally applied force overcoming the friction between the sleeves and the container wall. As is apparent, the safety means represented by the sleeve 6 becomes automatically effective when the burner is screwed into the position of Fig. 3.

While the invention has been described in detail with respect to a certain now preferred example and embodiment of the invention it will be understood by those skilled in the art after understanding the invention, that various changes and modifications may be made without departing from the spirit and scope of the invention, and it is intended, therefore, to cover all such changes and modifications in the appended claims.

What is claimed as new and desired to be secured by Letters Patent, is:

1. In combination with a gaseous fuel burning stove having a fuel storage container provided with a burner mounting socket at the upper extremity thereof, a pressure sensitive valve normally biased toward a closed position disposed within said socket, a burner threadingly secured in substantially sealed engagement within said socket maintaining said valve in an open position to permit the flow of fuel therethrough from said container to said

burner, a cooking vessel support secured to said burner above said container, a plurality of rigid legs each secured at one end to said support and having an opposite end extending toward the top of said fuel storage container, and elastic sleeves secured to and protruding axially beyond said opposite end of said legs into frictional engagement with said top of said fuel storage container to frictionally limit rotational movement of said burner relative to said socket.

2. In a gaseous fuel burning stove including a fuel storage container having a burner mounting socket at the opposite extremity thereof, said socket housing a valve normally biased toward a closed position, a burner threadingly secured in substantially sealed engagement within said socket maintaining said valve in an open position to permit the flow of fuel therethrough from said container to said burner, and a cooking vessel support secured to said burner above said container, the improvement including a safety device for impeding the rotational movement of said burner out of sealed engagement with said socket comprising, in combination, rigid legs fixedly joined at one end to said support and having an opposite end depending therefrom toward the top of said fuel storage container, and elastic sleeves fitted upon and protruding axially beyond said opposite end of each of said legs, each protruding sleeve portion adapted to frictionally engage with the top of said fuel storage container to limit rotational movement therebetween.

5 3. In a gaseous fuel burning stove including a fuel storage container having a burner mounting socket at the upper extremity thereof, said socket housing a valve normally biased toward a closed position, a burner threadingly secured in substantially sealed engagement within said socket maintaining said valve in an open position to permit the flow of fuel therethrough from said container to said burner, the improvement including a safety device for impeding the rotational movement of said burner out of sealed engagement with said socket comprising, in combination, a cooking vessel support secured to said burner above said container, rigid legs fixedly joined at one end to said support and having an opposite end depending therefrom toward the top of said fuel storage container, and elastic sleeves fitted upon and protruding axially beyond said opposite ends of each of said legs, each protruding sleeve portion adapted to frictionally engage with the top of said fuel storage container to limit rotational movement therebetween.
